Attorneys,

UNITED STATES PATENT OFFICE.

MATTHEW R. HULL, OF CONNERSVILLE, INDIANA, ASSIGNOR TO REX BUGGY COMPANY, OF CONNERSVILLE, INDIANA, A CORPORATION OF INDIANA.

LATCH FOR VEHICLE-DOORS.

1,154,398.

Specification of Letters Patent. Patented Sept. 21, 1915.

Application filed June 21, 1915. Serial No. 35,416.

To all whom it may concern:

Be it known that I, MATTHEW R. HULL, a citizen of the United States, residing at Connerville, in the county of Fayette and State of Indiana, have invented certain new and useful Improvements in Latches for Vehicle-Doors, of which the following is a specification.

This invention relates to improvements in closed bodies for passenger vehicles, and has particular application to removable or "sedan" tops for automobiles wherein the upper and removable portions of the doors, that is, those portions of the doors which belong to and come off with the removable top are frequently and in fact are generally in different planes from their lower portions, and the object of the invention is to connect the upper and lower door members adjacent their outer edges with a single latch which is operated by a single handle on the outside of the car, to make such connections adjustable whereby the two door-members may move differently without interference from said latch-mechanism, and to hold the latter elastically together with the latch-spring to prevent rattling.

I accomplish the above and other objects which will hereinafter appear by the mechanism illustrated in the accompanying drawing, in which—

Figure 1 is a side elevation of the major portion of an automobile body with a removable top, embodying my invention. Fig. 2 is an inside view on a larger scale of the doors shown in Fig. 1, adjacent the latch-mechanism which is also shown, and Fig. 3 is an edge-view of the door members of Fig. 2 with the latch members in corresponding relation.

Like characters of reference indicate like parts throughout the several views of the drawing.

The permanent body 4 is provided with a door 5 which is hinged thereto and is kept closed by a latch of usual construction comprising a bolt 6 shot out by a spring 7 and retracted by a lever 8 having a handle 9 accessible only from within the body. The equipment thus far is old and well-known. Removably secured to the body 4 is the sedan top 9 having a door-member 10 which registers with the door 5, and forms an upper extension thereof, the part 5 being what

I designate herein as the lower door-member 55 and the part 10 as the upper door-member.

To the inside of the upper door-member 10 I pivotally secure a bent lever 11, at its upper end. The lower end of the lever is expanded and provided with a slot 12 through which the handle 9 is passed. The latch bolt is retracted by swinging the lever inwardly or toward the hinges of the door-members and can be accomplished by inside passengers by direct manipulation of the lever. To operate the latch from the outside I pass a rock-shaft 13 through the door 5, on the outer end of which is a handle 14, and on the inner end a plate 15 having a cam-face in contact with the lever. This cam-face is preferably channeled to receive the lever which is held constantly against the cam by the action of the latch-spring 7. Lost motion and rattling is thereby prevented. The bend in the lever 11 is to bring the pivoted end over for attachment to the solid sash or frame of the door.

Where the angular relation of the planes of the upper and lower door members vary so as to make their separation excessive upon opening, thereby requiring a correspondingly long slot in the lower end of the lever, I form the latter without expanding and slotting its lower end and simply pass the lower end of the lever down between the cam and handle 9.

Having thus fully described my invention, what I claim as new and wish to secure by Letters Patent of the United States, is—

1. A vehicle door in two transversely divided members, a latch on the lower member comprising a bolt, a spring to shoot the bolt, and a lever to withdraw the bolt, in combination with a lever pivoted at its upper end to the upper door-member and engaging said first lever below, a cam against which said last lever is held by said latch-spring and manually operated means to rock the cam.

2. A vehicle door in two transversely divided members, a latch on the lower member comprising a bolt, a spring to shoot the bolt and a lever to withdraw the bolt said lever having a lateral projection at its end remote from the bolt, in combination with a rock-shaft passing through the door, a handle on its outer end, a cam on its inner end and a second lever pivoted at its upper end to the upper door-member and contacting at its

lower end with the lateral projection of the first lever and bearing against said cam.

3. A vehicle door in a plurality of transversely divided members, a latch on the lowest member comprising a bolt, a spring pressing the bolt normally to a shot position, and a lever to retract the bolt having a lateral projection at its end remote from the bolt, in combination with a cam on the inside of the door, means to rotate the cam from the outer sill of the door and a lever pivoted to the top member of the door and

bearing against the cam and slotted at its lower end, the lateral projection of the first lever passing through the slot in the second lever.

In witness whereof, I, have hereunto set my hand and seal at Connersville, Indiana, this 14th day of June, A. D. one thousand nine hundred and fifteen.

MATTHEW R. HULL. [L.S.]
